HOT-WELL PREHEATER AND CONDENSER
FOR LOCOMOTIVES

Edward F. Sullivan, South Portland, Maine

Application March 9, 1932. Serial No. 597,859

3 Claims. (Cl. 122—434)

The invention hereinafter to be described relates, in general terms, to apparatus by means of which a large percentage of the heat units contained in the condensate water, together with a considerable quantity of exhaust steam discharged through the condensate pipe extending rearwardly from the main water-heating unit of a locomotive may be advantageously utilized for feed-water pre-heating purposes.

A particular object of my present invention is to expedite the heating of the boiler feed water by segregating that portion which is being immediately drawn on in feeding the boiler, from the main tank supply, so that the pre-heating operation may be conducted in a comparatively small body of water which can be rapidly raised in temperature.

To accomplish the above mentioned object I provide what I designate as a hot-well—an enclosed tank-like structure, the capacity of which is relatively very small compared with that of the tank in which is stored the main supply, which latter is located in the tender of the locomotive. This hot-well element may be secured in any convenient location with respect to the larger tank—either beneath or at the bottom and on the inside of the latter, and in this smaller container I provide a pipe coil which receives the condensate, or water of condensation, together with more or less exhaust steam as it flows from the main feed-water heater toward the supply tank.

There is always open communication maintained between the hot-well and the main storage tank, thereby insuring a full and constant supply of water in the smaller of the two water-holding elements; feed-water, however, is drawn directly from the smaller one only.

Furthermore, in the operation of my apparatus I am enabled to condense and convert into usable feed-water a comparatively large part of the free exhaust steam which passes with the water of condensation through the condensate pipe, and this, so far as I am aware, has never before been accomplished.

The character of the invention may best be understood by reference to the description found in the following specification when taken in connection with the accompanying drawing in which is disclosed an embodiment which, at the present time, I consider preferable to other possible forms in which the invention might be carried out.

In the drawing,—
Fig. 1 is a fragmentary view, in side elevation,

of a locomotive equipped with apparatus according to my invention;

Fig. 2 is a fragmentary plan view, partly in section taken on line 2—2, Fig. 1, and

Figs. 3 and 4 are sectional elevations of the hot-well and coil showing slight modifications in the arrangement of the piping and method of attaching the hot-well to the bottom of the tender tank.

Similar reference characters are employed to identify like parts in all the different views of the drawing.

Referring to the drawing, B represents the boiler of a locomotive, T the tender tank containing the main supply of feed-water, and H a tubular exhaust steam heater of any of the various and well known types.

The pipe 1 is the element through which is conveyed from the heater H the product of partial condensation of the exhaust steam entering the heater from the power units, as the main driving engines, air pump and stoker engine, this product comprising condensate—exhaust steam condensed in the heater, as well also as a certain quantity of the uncondensed steam which passes along with the water of condensation toward the tank supply.

Continuing rearwardly, the pipe 1 has direct communication with the vertically disposed pipe 2 which extends upwardly through the bottom of the tank and through the water W therein, and bending, descends into the hot-well 3 and joins one end of the pipe coil 4. From the opposite end of this coil rises the pipe 5 extending upwardly above the highest normal level of the water W. The end terminates, preferably, in a half-turn 5a.

The bottom Ta of the tank T is perforated by one or more holes 6 through which water from the main tank flows by gravity to maintain a full supply in the hot-well 3, and the feed suction line 7 to the pump P makes connection with the bottom of the hot-well at 8.

To provide against clogging of the feed check valves by any foreign matter entering the main tank I supply a screen or strainer 9 which effectively operates to keep the feed lines clear of obstruction.

On the condensate pipe line 1 is an automatically operating suction-breaking cock 10 which provides against drawing condensate water back into the main heater when the main drive-engine's throttle is closed and the locomotive drifting or coasting with the valve gear set in reverse.

A manually operated drain cock 11 with extension handle 12 to actuate it supplies the means to

drain the condensate line of water during cold weather when the locomotive is exposed to the elements during a considerable period of inaction. The drain cock may be operated from the cab of the locomotive, into which the handle 12 extends.

Fig. 3 illustrates a slight modification from the structure shown in Fig. 1. In this instance the tender tank and hot-well being separated by the spacers 13, by a distance S, the cooler temperature of the tank water does not act so directly to lower the hot-well temperature as was the case in the previously described construction in which the contents of these two members were separated by the tank bottom T_a only. It is thus possible to maintain a higher temperature of hot-well water. A further difference between the two constructions resides in the manner of making the connection between the pipe line 1 and the coil 4, the pipe 2, in this case, being dispensed with and the condensate line connected directly on to one end of the coil 4, the pipe 5, however, being similar in the two designs.

In operation, the feed-water is drawn directly from the hot well by the feed-pump P through the pipe line 7, and as it is withdrawn from the hot-well it is replaced by more water from the main supply tank T, the water falling by gravity through the openings 6. In the course of operating the locomotive a portion of the exhaust steam from the power units condenses in the main heater H and this, together with more or less of the uncondensed steam under considerable pressure passes out of the heater through the condensate pipe 1. The pressure in the exhaust chamber of the heater forces the water and uncondensed steam through the pipe 2 and into the coil 4—or as in the modified form, directly into the coil, where two actions, relatively differing in effect occur.

In the first place the water in the hot-well becomes raised in temperature by absorbing the heat radiated from the coil containing the hot condensate and steam, and as a sequence the second action develops, in which the steam having given off its surplus heat condenses in the coil and passes outwardly of it into the main supply tank increasing the available supply of feed-water.

The smaller body of water in the hot-well will, obviously, heat more rapidly and supply the feed pump with a higher temperature feed water than would be the case in which the same coil was placed in the larger, main tank T; so, for very apparent reasons, a higher efficiency is possible in the operation of the heater than would otherwise obtain. The result is somewhat analogous to that obtained with an automatic gas heater for water in which the water is heated only as it is being drawn from the tank, in contrast to attempting to heat the whole body of water and maintain a high degree of temperature constantly therein.

In Fig. 4 an alternative arrangement respecting the location of the hot-well is shown. In this case this element is positioned on the top side of the tank bottom, and is thus submerged in the water of the main supply container. This is objectionable for the reason that it is impossible to heat the water in the hot-well to so high a temperature as would obtain were the latter somewhat

isolated from the main tank. It offers this advantage, however, in that possible interference with the running gear of the tender or other obstructions beneath the main tank is avoided.

Construction as illustrated in Figs. 1 and 3 is preferred on account of the fact that in either of these instances the hot-well may be easily covered with insulation I, thereby making it possible to greatly increase the efficiency of the pre-heater.

The apparatus, it is believed, is calculated to effect a considerable saving in the operation of locomotives as heat ordinarily wasted is in this case conserved and put to a useful purpose and more or less of the exhaust steam, which, in the conventional method of operating feed-water heaters is considered of no particular account, is condensed and also made an asset by materially adding to the supply of water carried on the locomotive.

What I claim and desire to secure by Letters Patent is:

1. A hot-well preheater and condenser for locomotives having a main water-supply tank and a main feed-water heater, comprising a relatively small tank disposed beneath said main water-supply tank, a pipe coil in said small tank through which hot condensate water and exhaust steam from the main feed-water heater of said locomotive travels on its course to the said main supply tank, a discharge pipe from said coil rising through the water in said main supply tank and terminating at an elevation above the highest normal level of the water in said supply tank, a pipe through which feed-water may be discharged from said small tank, and means of communication between the interiors of said small tank and said main water-supply tank.

2. A hot-well preheater and condenser for locomotives comprising in combination with the main water-supply tank and the feed-water heater for said locomotive, a relatively small capacity tank located beneath the said main supply tank, a pipe coil in said smaller tank, means to admit water of condensation and exhaust steam from said feed-water heater to said coil, a pipe connection adapted to admit water by gravity from the said main supply tank to the said smaller tank, a discharge opening in said smaller tank through which water in which said coil is submerged may be fed to the feed-water line of said locomotive, and means to conduct and discharge the water of condensation in said coil to said main supply tank at an elevation above the high normal level of the water therein.

3. A hot-well preheater and condenser for locomotives comprising in combination with the main feed-water heater and the main feed-water-supply tank therefor, a small tank located beneath and in spaced relation to said main supply tank, a condensate pipe line connected to said main feed-water heater, a pipe coil positioned in said small tank and connected to said condensate pipe line, means to admit water by gravity from the said main water supply tank to the said smaller tank, a pipe extending from the exit end of said coil into said main supply tank, and means for conveying water in said smaller tank to the feed-water pump of said locomotive.
